(57) **CLAIM**

The ornamental design for a hearing aid, as shown and described.

DESCRIPTION

FIG. 1 is a rear view of a hearing aid showing our new design;
FIG. 2 is a left side view thereof;
FIG. 3 is a front view thereof;
FIG. 4 is a top view thereof;
FIG. 5 is a right side view thereof;
FIG. 6 is a bottom view thereof; and,
FIG. 7 is a perspective view thereof.

The broken lines in FIG. 3 represent the unclaimed portions of the hearing aid and form no part of the claimed design.
